(57) **CLAIM**

The ornamental design for a bottle, as shown and described.

DESCRIPTION

The application relates to a bottle for use as a container.

FIG. 1 is a perspective view of a bottle showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

The broken lines showing the pour spout in the FIG. 1-6 drawing views and of the bottom surface in the FIG. 7 drawing view included for the purpose of showing environmental structure that forms no part of the claimed design.
